UNITED STATES PATENT OFFICE.

GUSTAVE BLUEMEL, OF TOLEDO, OHIO, ASSIGNOR TO FERGUSON FURNACE COMPANY,
OF TOLEDO, OHIO, A CORPORATION OF DELAWARE.

HEATER AND KINDLER.

Application filed June 27, 1921. Serial No. 480,680.

To all whom it may concern:

Be it known that I, GUSTAVE BLUEMEL, a citizen of German Austria, residing at Toledo, in the county of Lucas and State of Ohio, have invented certain new and useful Improvements in Heaters and Kindlers, of which the following is a specification.

This invention relates to certain new and useful improvements in apparatus for mixing air and a fluid such as crude oil and for supplying the same under pressure for various uses.

The invention is particularly designed to furnish a portable apparatus of simple and efficient construction for use in setting tires, straightening frames and heating metal for many other purposes, also for kindling fires in locomotives, and in many other ways.

One of the primary objects of the invention is to provide a valve of simple construction which can be easily made and operated to control the length and intensity of the flame and adapt the apparatus for a variety of different uses.

And further objects of the invention are to control the mixture of air and fluid by the operation of a single valve so that a desired mixture may be constantly maintained adapted to the particular work then being performed; to thoroughly mix the air and fluid in the valve and deliver the same in a thoroughly atomized condition to the burner; and to provide simple means for cleaning the valve at the conclusion of the operation.

In the accompanying drawings I have illustrated the invention in a sectional view and referring thereto 1 is a fluid tank preferably mounted on wheels so that it can be easily transported from place to place. A valve body designated generally 2 is secured in the top of the tank and it is provided with an air chamber 3 and a mixing chamber 4. An air line 5 is connected at 6 to the valve body and communicates through a passage 7 with the air chamber. A passage 8 connects the air chamber with the tank. A stem 9 provided with a hand wheel 10 on its outer end threadedly engages the valve body and carries a double cone valve 11 which engages an opening 12 in a partition 12' between the air chamber and the mixing chamber and also a shoulder 13 at the other end of the air chamber. The wall of the opening adjacent the air chamber forms a seat

12' for the valve 11. A fluid passage 14 connects the mixing chamber with a pipe 15 which is secured in the valve body and extends down within the tank adjacent the bottom thereof. A stem 16 provided on its outer end with a hand wheel 17 threadedly engages the valve body and carries on its inner end within the chamber a valve 18 which seats in the adjacent end 19 of the passage 14. A delivery hose 20 is connected to the valve body and communicates through a passage 21 with the mixing chamber 4. This delivery hose is preferably connected to one end of a metal pipe which carries on its other end a suitable burner, the pipe being employed for handling the burner in actual use and directing the flame as desired.

When the air valve 11 is seated against the shoulder 13 the air supply will be cut off. To start the apparatus in operation, the fluid valve 18 remaining open, the air valve is moved forward from its seat 13 to its seat in the opening 12 thereby admitting air pressure from a suitable source of supply through the pipe 5, the passage 7, the air chamber 3, and the passage 8 to the tank. This pressure soon forces the fluid up through the pipe 15 and the passage 14 into the mixing chamber 4, and as soon as this flow is well started the air valve 11 is withdrawn from its seat in the opening 12 and allowed to remain between this seat and the seat 13 so that the air may flow through the opening 12 directly into the mixing chamber where the tank fluid is thoroughly atomized and carried out through the delivery hose to the burner. The area of the opening 12 is greater than the area of the opening 21 and by adjusting the valve 11 different degrees of pressure may be established in the air chamber 3 and the mixing chamber 4 so that a greater or less quantity of fluid will be forced up into the mixing chamber.

The fluid valve 18 is employed for controlling the amount of oil used. When the operation is completed the fluid valve 18 is closed and the air is permitted to flow freely through the opening 12 and the mixing chamber to blow out surplus oil which may remain therein and in the delivery hose and burner.

My invention provides an apparatus of simple construction which can be easily manufactured and assembled at comparatively low cost. The valves are arranged

for convenient operation so that the length and intensity of the flame can be easily and efficiently controlled. The apparatus is very useful around railway shops and manufacturing plants because of its portability and because it can be utilized for quickly applying an intense heat for bending and repairing metal parts. It can also be used around shops and plants for many other purposes and it may also be used for kindling fires in locomotives.

It is customary to use crude oil in the tank but I may use any equivalent therefor and also any equivalent for the air pressure here-
15 tofore described.

I have shown the valve body made up of three parts threadedly engaged as a convenient method of manufacture but I reserve the right to make the valve body otherwise 20 and to make other changes in the form, construction and arrangement of parts which fairly fall within the scope of the following claims:

I claim:

- 25 1. The combination with a fluid supply tank, of a valve connected with the tank and with a source of compressed air supply, said valve comprising a body having an air chamber having independent communications with the air supply and with the tank, a mixing chamber having a communication with the bottom of the tank and also having a delivery outlet independent of said communication, a direct communication between 30 the air chamber and the mixing chamber, and a double acting valve operating in the air chamber for closing said air supply communication or said direct communication.
35 2. The combination with a fluid supply tank, of a valve connected with the tank and with a source of compressed air supply,

said valve comprising a body having an air chamber communicating with the air supply and also with the tank, a mixing chamber communicating with the tank and having 45 a delivery outlet, a partition between said chambers and having an opening therein, and a valve operating in the air chamber adapted to be seated in said opening to direct the flow of air through the air chamber 50 into the tank, and adapted to be unseated to permit the flow of air directly from the air chamber into the mixing chamber.

3. The combination with a fluid supply tank, of a valve connected with the tank and with a source of compressed air supply, said valve comprising a body having an air chamber communicating with the air supply and with the tank, a mixing chamber communicating with the tank and having a delivery 60 outlet, a communicating opening between the air chamber and the mixing chamber, and a valve in said air chamber adapted to be operated in one direction to close the air supply to the mixing chamber and in the 65 other direction to close the opening between the air chamber and the mixing chamber.

4. The combination with a fluid supply tank, of a valve connected with the tank and with a source of compressed air supply, said valve comprising a body having an air chamber communicating with the air supply and with the tank, a mixing chamber, a passage connecting the mixing chamber with the tank, a valve in the air chamber for controlling the 75 flow of fluid through said passage, an opening forming a communication between the air chamber and the mixing chamber, and a double acting valve for closing said air supply communication or for closing said com- 80 municating opening.

GUSTAVE BLUEMEL.
